United States Patent Office.

CHARLES T. ULMANN, OF NEW YORK, AND MARCUS BOCKMAN, OF BROOKLYN, NEW YORK.

Letters Patent No. 75,657, dated March 17, 1868.

IMPROVEMENT IN HAND-ENGINE.

The Schedule referred to in these Letters Patent and making part of the same.

TO ALL WHOM IT MAY CONCERN:

Be it known that we, CHARLES T. ULMANN, of the city of New York, county of New York, and in the State of New York, and MARCUS BOCKMAN, of the city of Brooklyn, county of Kings, and in the State of New York, have invented a new and useful Improvement in Hand-Engines; and we do hereby declare the following to be a full, clear, and exact description of the same, reference being had to the accompanying drawings, (three sheets,) making a part of this specification, in which—

Figure 1 is a side elevation.

Figure 2, a side elevation of part of the hand-engine.

Figure 3, a perspective view of the main lever.

Figure 4, a side elevation of the crank with connecting levers.

Figure 5, an end elevation of part of the engine.

In all the figures in the drawings the letters of reference employed denote identical parts.

Our invention consists of the construction of a hand-engine worked by means of levers, arranged in such a manner that but little force is required to start and to keep the engine's working parts going.

To enable others skilled in the art to make and use our invention, we will proceed to describe its construction and operation.

Our hand-engine consists of two vertical rectangular frames or standards A, supporting the machinery, and placed far enough from each other to allow the machinery to work. Each frame, A, consists of two parts, a lower and an upper one, well secured to each other. The lower frames, A, incline towards each other at their upper parts, spreading out at the base in order to give a stronger rest for the upper frames A'. Both frames are placed in a parallel position towards each other, and well secured to each other with braces, &c. B is a triangular piece, and used as a crank or quarter crook. At its lower points C' it is attached to arms C, as shown in figs. 1, 2, 4, and 5.

The shaft N, which rests in bearing N on the upper part of the lower frames A A, forming a right angle with the frames, projects over both frames, and at each of its ends supports a wheel, M, which may be used as a fly-wheel. At each end, and between the lower frames, a main lever, E, is hung on a bolt or pivot, E'', by means of arms D and C. The lever E is connected with the crank B.

When the machine is not worked, the main lever E will occupy a vertical position, as shown in fig. 1, and fig. 2 shows the lever E in an inclined position. At its lower end, the lever E is provided with a projection, forming a right angle with the shaft of the lever E. The size of this projection or weight will determine the power. By increasing or decreasing the size or weight of said projection the power will be increased or decreased.

The main lever E is at its upper part, a little below the pivot E', provided with a joint, E', which might be useful in case the engine were placed on any swimming-surface. The joint or hinge E, shown in fig. 3, will allow the lower part of the lever to swing sideways, and in such case the frames A must be put far enough from each other, and so constructed that they do not interfere with the motions of the lever E. In figs. 2 and 3 another shape of lever E is shown than in fig. 1.

The lever E is actuated by arms L L, which are pivoted at E'' to minor arms E' E', secured to the upper part of levers E E. The connecting-rods or arms L are at their upper ends provided with slots L' L', in which a bolt or pin, I, moves; the bolt I resting in socket E, which is firmly attached to the lower point of a frame or working-beam, G. This frame is constructed like a rhomboid; its sides are curved outwards, and provided with slots G' G'. The working-beam G is at its upper point pivoted to the vertical upper frames A' A', where it hangs suspended, and allowed to oscillate when worked upon by levers H.

The handles K, by which the engine is worked, are pivoted to the upper part of the vertical frames A' A' at K', and at their upper parts provided with arm I, as shown in fig. 1. This arm I projects towards the inner part of the machine, and has points I', which work in slots H''.

H H are levers of a triangular form, pivoted near each other in the upper part of the vertical frames A', a little below the pivots K'. Friction-rollers I'' and H'' are secured in arm I, in such a manner that it touches

the upper face of lever H and frame G. At their lower ends the levers H are provided with a rectangular projection, in which a pin, H', is inserted, and said pins H' working in slots G'.

When the arms K are moved up and down, the machinery is put in motion, the movements of the arms K will communicate an oscillating motion to the levers H, and the motion through pins H' working in slots G', will actuate upon the working-beam G. Arms L connected through the socket F will, when said socket commences to oscillate, also be put in motion, and thereby working the main levers E. Thus worked upon, the levers E will, through the agency of arms D and C, revolve the crank B, and the axle and fly-wheel M thereby put in motion.

We do not confine ourselves to the precise mode of construction of our improvement, nor the particular use; but

What we claim, and desire to secure by Letters Patent, is—

1. The combination of handles K, projections I, levers H, working-beam G, socket E, and arms L, when arranged as and for the purpose set forth.
2. The main lever E, when constructed as and for the purpose set forth.
3. The combination of arms D and C, and the triangular crank or quarter-crook B, when arranged as and for the purpose set forth.

CHARLES T. ULMANN,
M. BOCKMAN.
